UNITED STATES PATENT OFFICE.

WILLIAM S. BECHTOLD, OF NEWARK, NEW JERSEY.

BARRETTE.

No. 922,838.

Specification of Letters Patent.

Patented May 25, 1909.

Application filed November 28, 1908. Serial No. 464,930.

To all whom it may concern:

Be it known that I, WILLIAM S. BECHTOLD, a citizen of the United States, and a resident of Newark, in the county of Essex and State 5 of New Jersey, have invented certain new and useful Improvements in Barrettes, of which the following is a specification.

My invention relates to barrettes, and more particularly, to the hinge piece to which 10 the tongue or pin of the barrette is pivoted and to the hook adapted to receive said tongue or pin. These members, as at present constructed, consist of a thin piece of tortoise shell, celluloid or the like (it being de- 15 sirable that the upper portion, at least, be relatively thin), the upper part of which is cut or formed to the required shape and the base of which is cemented to the body of the barrette. This construction of the member 20 possesses very serious disadvantages, however, in that this comparative thinness renders them fragile; and the relatively small securing surface of their base, due to the thin material used, offers but a small holding 25 surface, causing the hinge piece or the hook to very readily break off and thereby render the barrette useless.

It is the object of the present invention to so construct the said members that the de- 30 sirable, relatively thin upper portion is re- tained, but a substantial reinforcement is provided for same, and that the adhering surface is such that the members are not readily broken off. Several forms of such 35 members are illustrated in the accompanying drawings, in which—

Figure 1 is a side elevation of a barrette with my improved members attached. Fig. 2 is a view of the hook end of the barrette. 40 Figs. 3 and 4 are detail views of the hook member shown in Figs. 1 and 2.

Similar characters of reference designate corresponding parts throughout the several views.

45 Referring now to the drawings, Figs. 1 to 4, 10 designates the back or body portion of a barrette, and 11 the tongue or pin. This tongue or pin 11 is pivotally connected to a hinge piece 12, and is adapted to be held by a

hook 13. The hinge piece and hook each 50 consist of two parts, Figs. 3 and 4,—an upper and inner part 14 which is relatively thin as required and cut or formed to the desired shape; and a lower part 15, provided with a recess or slot 16, adapted to receive and reinforce the upper part 14, the same being cemented to the said part 15 so that they are in effect one piece. The lower part 15 is made with the required securing surface to prop- 55 erly hold the said members. 60

I claim:

1. In a barrette comprising a back or body portion, a hook, and a pin or tongue, a fastening member consisting of two parts struck from sheet material, one being the upper and holding portion adapted to pivotally hold said pin or tongue, and the other forming the base, having a large securing surface and a recess through said base adapted to snugly receive and retain said upper part with the 65 lower end flush with the underside of the base, whereby the base and upper part may be simultaneously secured to the back or body portion, by cement or the like.

2. In a barrette comprising a back or body 75 portion, a pin or tongue, means for pivotally connecting said pin or tongue to the body portion, a hook consisting of two parts struck from sheet material, one being the upper or hook portion adapted to receive said pin or 80 tongue and comprising a thin upper part bent in the shape of a hook and the other forming the base, having a large securing surface and a recess extending through said base adapted to snugly receive and retain said upper part 85 or hook portion with the lower end flush with the underside of the base, whereby the base and hook portion may be simultaneously secured to the back or body portion by cement 90 or the like.

Signed at Newark, in the county of Essex and State of New Jersey this 21 day of November A. D. 1908.

WILLIAM S. BECHTOLD.
